(57) **CLAIM**

The ornamental design for a refractory anchor brick as shown and described.

DESCRIPTION

FIG. 1 is a front perspective of the refractory anchor brick showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The clip element shown in broken lines in FIG. 1 is included for the purpose of illustrating environment and forms no part of the claimed design.

FIGS. 1-6 contain symbolic break lines in the form of dot-dash lines. The portion between the break lines forms no part of the claimed design.
